(57) **CLAIM**

The ornamental design for a chaise lounge, as shown and described.

DESCRIPTION

FIG. 1 is a perspective view of a chaise lounge; FIG. 2 is a right side view of the chaise lounge shown in FIG. 1, the left side being a mirror image thereof;

FIG. 3 is a top view of the chaise lounge shown in FIG. 1; FIG. 4 is a bottom view of the chaise lounge shown in FIG. 1; FIG. 5 is a front view of the chaise lounge shown in FIG. 1; and,

FIG. 6 is a rear view of the chaise lounge shown in FIG. 1. The stippling is to show surface texture and is not a necessary part of the design.
